USSN 191,640 filed May 9, 1988 entitled "Encased Pool Chemical Tablet with Domed Ends" by John M. Casberg.

Primary Examiner—Susan J. Lucas
Assistant Examiner—M. H. Tung

[57] CLAIM

The ornamental design for a shell encased pool chemical tablet, as shown and described.

DESCRIPTION

FIG. 1 is a top perspective view of a shell encased pool chemical tablet showing my new design;

FIG. 2 is a side elevational view thereof, the other side being identical;

FIG. 3 is an end elevational view thereof, the other end being identical; and,

FIG. 4 is a top plan view thereof.

FIG-1

FIG-2

FIG-3

FIG-4
